[57] CLAIM

The ornamental design for a fly-trap, as shown and described.

DESCRIPTION

FIG. 1 shows a perspective view of the fly-trap seen at an angle from above;

FIG. 2 shows a side view of said fly-trap;

FIG. 3 shows a top plan view of the fly-trap corresponding to the direction of arrow III in FIG. 1;

FIG. 4 shows a bottom plan view of the fly-trap corresponding to the direction of arrow IV beneath FIG. 1.

FIG. 5 shows the fly-trap according to FIG. 1 also in perspective view but provided with a suspension hook; FIG. 6 shows a vertical section through the fly-trap according to FIG. 1.
